UNITED STATES PATENT OFFICE.

JOHN R. LONG, OF KENMORE, OHIO.

VICE.

Application filed January 29, 1923. Serial No. 615,642.

To all whom it may concern:

Be it known that I, JOHN R. LONG, a citizen of the United States, residing at Kenmore, in the county of Summit and State 5 of Ohio, have invented certain new and useful Improvements in a Vise, of which the following is a specification.

My invention pertains to an improvement in vises, and particularly in vises of the type 10 heretofore patented by me and disclosed in my Letters Patent No. 667,152, my object being to simplify the construction and assembly of parts and more effectively lock the vise against rotation in the vertical and 15 horizontal positions in which it is adapted to be placed and used upon its supporting post.

In the annexed drawing, Fig. 1 is a vertical section longitudinally through the body 20 of the main vise parts, and Fig. 2 is a vertical section transversely of the vise on line 2—2 of Fig. 1. Fig. 3 is a horizontal section of the vise on line 3—3 of Fig. 1. Fig. 4 is a perspective view of the integral locking element and nut. Fig. 5 is a reduced view showing the body of the vise in a horizontal position on the post.

The vise comprises a body 2 having a fixed jaw 3 and an integral extension 4 at its front side opposite a substantially square opening 5 which extends through the body from the rear and is adapted to receive and guide the hollow extension 6 of the movable jaw 7. The operating screw 8 is housed 30 within extension 6 and has a round enlargement 9 seated within a round recess within the front side of the movable jaw, and a locking pin or screw 10 extends transversely through the front end of the jaw and rests 35 within an annular groove 11 in enlargement 9, thereby permitting the screw to be turned but preventing the screw from being withdrawn from its socket. The enlargement 9 however, bears against the inner end 40 of the socket in clamping operations and the pin is not subjected to any strain at this time. The screw-threaded end of the screw passes through a screw-threaded opening in the upper end of a locking member 12 which 45 is mounted at its lower end upon a pivot pin 14 extending transversely through the flanged sides 15—15 of body 2. The locking member 12 is located at the rear side of the body opposite and parallel with a round vertical bore 16 extending upwardly 50 from the bottom of the body, and the inner

vertical face 17 of the locking member is curved longitudinally to fit the round face of the supporting post 19 of a stationary base member 18 upon which the vise is 50 adapted to be rotated to different working positions. Locking member 12 is relatively long and is pivoted at its bottom end relatively near the lower end of body 2 to enhance the locking effect at the upper end 65 of the post as near the screw as possible. Thus the more distant the pivot pin is located from the screw the greater the arc movement of the locking member at the upper end of the post and the tighter the grip 70 on the post, and when the post and locking member are accurately made only a slight rocking movement of the locking member is required to effect locking. However, this action does not occur until the final clamping movement of jaw 7 upon the work. A slight play exists between the co-acting 75 screw-threads and also at the socket end of the screw, which permits the slight rocking movement required by the locking member, 80 and a slight loose play may also be provided at the pivot pin. In clamping the jaws and locking the body of the vise upon the post to prevent rotation the movable jaw is solidly supported at its front and 85 heavier end by the integral extension on body 2 and the said jaw is also closed at its bottom where resting and sliding upon said extension. Thus in clamping the work between the jaws no tilt occurs in the movable 90 jaw and the work is not disturbed or displaced from its predetermined setting, for example for a templet and the part to be operated upon.

The vise is also particularly constructed 95 to permit it to be supported in a rotatable horizontal position as shown in Fig. 5. Thus body 2 has round bosses 20—20 upon opposite sides and a round bore 21 transversely of vertical bore 16 intermediate the 100 upper and lower ends thereof where locking engagement of the post may be effected by the locking member intermediate its pivot pin and the clamping screw. To obtain effective locking in this position on the post the locking member is formed with a curved locking surface 22 transversely of its longitudinally curved face, see Fig. 4, and the curvature in both instances corresponds to the diameter of the post and the bores for 105 the post. The vise may be laid horizontally 110 on either of its sides or supported in a ver-

tical position, and a secure locking effect is obtained on the post in each of these positions by the use of a long locking member pivoted and arranged at the rear side of the body as herein shown and described.

This result is further aided by the stable seating position of the slideable jaw upon the immovable integral extension 4.

What I claim, is:

- 10 1. A vise, comprising a body having an opening extending horizontally therethrough from front to rear and round intersecting bores extending vertically and transversely within its bottom portion and a vertical slot at its rear open to said horizontal opening and both bores, said body also having a fixed jaw at its upper end and an integral extension at its front opposite said horizontal opening, a movable jaw having 20 a hollow extension projecting through said horizontal opening and seated upon the integral extension of said body, an operating screw extending through the front end of said movable jaw into said hollow extension, 25 a locking member having a screw-threaded opening at its upper end for said screw and a pivot pin at its lower end engaged with the bottom portion of said body, said locking member occupying said vertical slot at the rear of said body and having a curved clamping face longitudinally thereof above said pivot pin opposite the rear side of the

vertical bore and also a curved clamping face transversely thereof opposite the transverse bore intermediate the pivot pin and said screw, and a supporting base for said vise having a round post of approximately the same diameter as said bores.

2. A vise, comprising a body having a fixed jaw and an integral supporting extension at its front side and a through opening rearwardly and above said extension, a slideable jaw member having a hollow extension open at its bottom approximately half its length at its rear end and seated at its closed end upon said integral extension, an operating screw rotatably mounted within said slideable member, a vertically-extending locking member confined at its upper end within the rear end of said hollow extension and pivotally connected at its lower end to the rear part of said body, said locking member having direct screw-connection with said operating screw and said body having round intersecting bores extending transversely and vertically therein opposite and open to said locking member, and a support for said vise having a round post to fit within said bores and adapted to be engaged by said locking member.

In testimony whereof I affix my signature hereto.

JOHN R. LONG.
